US0D1023680S

(12) United States Design Patent (10) Patent No.: US D1,023,680 S
(45) Date of Patent: * Apr. 23, 2024

(54) TUMBLER

(71) Applicant: YETI Coolers, LLC, Austin, TX (US)

(72) Inventors: Cody Jinkins, Austin, TX (US); Liza Morris, Austin, TX (US); Dustin R. Bullock, Austin, TX (US)

(73) Assignee: YETI Coolers, LLC, Austin, TX (US)

() Term: 15 Years

(21) Appl. No.: 29/860,486

(22) Filed: Nov. 18, 2022

Related U.S. Application Data

(63) Continuation of application No. 29/753,700, filed on Oct. 1, 2020, now Pat. No. Des. 977,912.

(51) LOC (14) Cl. 07-01

(52) U.S. Cl.

USPC D7/533; D7/510

(58) Field of Classification Search

(57) CLAIM

The ornamental design for a tumbler, as shown and described.

DESCRIPTION

FIG. 1 is a top, front, right perspective view of a tumbler showing our new design;

FIG. 2 is a top, rear, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of the tumbler form no part of the claimed design.

1 Claim, 8 Drawing Sheets

US D1,023,680 S
